(57) **CLAIM**

The ornamental design for the hinged lid, as shown and described.

DESCRIPTION

FIG. 1 is a perspective view of a hinged lid in accordance with my design;

FIG. 2 is a front elevation view of the hinged lid in accordance with my design;

FIG. 3 is a left side elevation view of the hinged lid in accordance with my design;

FIG. 4 is a right side elevation view of the hinged lid in accordance with my design;

FIG. 5 is a rear elevation view of the hinged lid in accordance with my design;

FIG. 6 is top plan view of the hinged lid in accordance with my design; and,

FIG. 7 is a perspective view of the hinged lid in accordance with my design, in a partially open position.

The broken lines showing environmental structure are for illustrative purposes and form no part of the claimed design.
